UNITED STATES PATENT OFFICE.

JAMES MCLENNAN, OF POLAND, AND EDWARD J. PEASE, OF NILES, OHIO.

GAME.

Application filed July 11, 1922. Serial No. 574,152.

To all whom it may concern:

Be it known that we, JAMES MCLENNAN and EDWARD J. PEASE, both citizens of the United States, residing, respectively, at Poland, in the county of Trumbull and State of Ohio, and Niles, in the county of Trumbull and State of Ohio, have invented a new and useful Improvement in a Game, of which the following is a specification:

10 This invention relates to a game device. The object of the invention is to provide a device with which an intellectual game may be played either in competition or as a form of solitaire; such game being susceptible of numerous variations in the actual playing thereof.

In the accompanying drawings Figure 1 is an isometric plan view of one arrangement of the device, showing the elements 20 thereof in proper position for beginning a game; Figure 2 is a similar view illustrating the first step in playing a game either in competition or as solitaire; Figure 3 is an isometric view of one of the pieces forming elements of the device; Figure 4 is an isometric plan view illustrating an alternative form of the device embodying a different arrangement and character of the pieces forming elements of the device; Figure 5 is a similar view illustrating another modification in the character and arrangement of the pieces; Figure 6 is a similar view illustrating a still further modification in their character and arrangement; and Figure 7 is a 30 detail view of means for moving pieces formed as shown in Figures 4, 5, and 6.

The device as shown in Figures 1 and 2 of the drawings comprises a box or container B of suitable depth to receive a set 40 of blocks C. On the inner side of the lid D of the box are a chart E and a pivoted pointer or needle F arranged to cooperate with the chart.

In this variation of the device the blocks 45 C are numbered consecutively from 1 to 15, with a 0 block which serves as a filler to cause the blocks to completely fill the box or container B. The chart E is laid off to provide a ring G concentric with the pin 50 upon which the pointer F is pivoted. This ring is laid off in sections corresponding in number to the designating numbers of the blocks or pieces of the set. Corresponding with each of the sections of ring G is an 55 arbitrary number marked on the chart. As shown, these numbers begin with the num-

ber "fifteen" and continue around the ring in clockwise direction and in arithmetical progression, all of the numbers being multiples of "fifteen," such series of numbers 60 as a whole, being designated by the reference letter T.

Before beginning play the blocks C are so arranged that the numbers thereon run consecutively, as shown in Figure 1 of the 65 drawings. The pointer or needle F is then spun and allowed to come to rest upon the chart E. As shown in Figure 2 of the drawings, the opposite ends of the pointer will point out two numbered spaces in the ring 70 G. The 0 block is then removed from the box and the indicated change or changes in the position of the blocks is made.

In one manner of playing the game the two blocks bearing the numbers indicated 75 by the pointer are transposed in their positions in the box or container B. Thus in the position of the pointer shown in Figure 2, the positions of the blocks numbered "2" and "10" are transposed. The object of the 80 game is then to restore these blocks to their original position in sequence by sliding them in the container, and without lifting them from the container. The blank space left by the removal of the 0 block obviously permitting the shifting and rearrangement of the blocks one at a time in effecting the desired restoration. The object is not attained until not only are the displaced blocks 85 restored to position, but the other blocks have 90 also been finally shifted into their proper positions in sequence.

With the arrangement shown in Figures 1 and 2 of the drawings the game may be 95 played to restore the blocks to position simply in the least number of moves, the shifting of any one of the blocks into the space vacant at any particular moment counting as a move. If desired, however, the object may be to restore the blocks to position in 100 less than a total number of moves, this total being secured by the addition of the two numbers indicated by the series T on the chart F outside the ring G thereon. In the latter instance a player's score is computed by subtracting the number of moves 105 actually expended from the allotted number in the series T indicated by the pointer F.

The game may also be played with the arrangement of Figures 1 and 2 of the drawings by merely shifting one of the blocks 110 the number of which is indicated by the

pointer into the exact space left vacant by the removal of the 0 block. In such case the score of the player shifting the pieces is the difference between the number of 5 moves indicated by the end of the pointer opposite to that indicating the designating or serial number of the block which is to be shifted and the number of moves actually expended in restoring the blocks to relative 10 sequential position.

It will be noted, for example, that if either of the blocks 12 or 15 is indicated, the player who has designated such block by his spinning of the pointer F scores a large number 15 of points.

It should be noted that all of the blocks C are provided on their upper face with a button or finger hold H, to provide a convenient handle for lifting the blocks in their 20 transposition and for sliding the blocks in working them into their proper position in sequence.

In Figure 4 of the drawings there is 25 shown a modification or variation of the device which combines the general features of the device as previously described with the general features of a picture puzzle. This modification or variation of the device comprises a box or container B similar to the 30 box or container previously described. A pointer or needle F' is also similarly mounted to be spun on a pivot pin in the lid D' of the box. Concentric with the pivot pin of the pointer or needle F' is an annular 35 chart 3, which is divided into a plurality of sections, each of these sections containing a designating number which corresponds to the designating number on one of the blocks or pieces K which fill the box or container 40 B'.

It should be noted that the blocks or pieces are not arranged in such order that the numbers thereon run in regular sequence throughout the set. When in proper position in the container B', however, all of the 45 numbered blocks or pieces K together form the outline map of the United States. There are one or more blank blocks or pieces, specially designated K¹, which bear neither any lines going to form the map itself nor any 50 designating number.

In playing the game the pointer or needle K is spun and the two pieces indicated thereby are transposed in their positions in the 55 container B'. One or more of the blank blocks K¹ are then removed from the container to allow space to shift the blocks slidably. In attempting to restore the displaced blocks to proper position the map 60 is completely disintegrated. The game thus presents the additional intricacy and difficulty of a picture puzzle. The difficulty of the game may be decreased, if so desired, by removing two or more of the blank blocks 65 instead of a single one thereof.

It will be noted that the chart J is not shown as provided with any numbers apportioning a definite number of moves. Such numbers may be added to the chart, equally as well as in the form of the device 70 illustrated in Figures 1 and 2 of the drawings, and are preferably so added.

It will be understood that instead of a map of the United States, a map of a State or foreign country, or a picture device or legend may be imposed upon the blocks used in this variation of the device. The device may be readily adapted to advertising purposes by the imposition of a trademark, advertising slogan or the like. 80

In the modification or variation of the device illustrated in Figure 5 of the drawings the box or container B² contains blocks L bearing the names of the months of the year arranged in sequence, and a plurality of 85 blank filler blocks L¹. On the lid B² a pointer E², mounted similarly to the pointers of the other variations of the device, and an annular chart M concentric with the mounting of the pointer E. The annular chart M is divided into twelve sections; each 90 of which bears the name of a month of the year.

In Figure 5 of the drawings the pointer is shown as having been spun, and as indicating the transposition of the blocks L bearing the names of January and July. The game as provided with these special blocks is played in the same manner as with the blocks C and J; that is, the blocks are 95 shifted without being lifted from the container until all the months of the year are arranged in sequence, and the number of moves necessary in effecting this rearrangement counted.

It should be noted that this variation or modification of the device presents an educational value, which renders it peculiarly suited to use by children. The provision of three blank filler blocks, and the relatively 100 small number of significant blocks, renders the rearrangement of the blocks L less difficult than the rearrangement of the blocks C and J in the previously described variations of the device, thus further rendering it adaptable to use by children. 115

The modification of variation of the device shown in Figure 6 comprises a box or container B³, and a pointer or needle F³ similar to those of the previously described modifications. The blocks or pieces N of this modification or variation, however, bear the letters of the alphabet and the sections of the annular shaft P, on the lid D³ are correspondingly marked. Two blank filler blocks N¹ are shown; but it will be readily understood that the additional number of these blank blocks or pieces may be increased by the addition of either an additional vertical row of blocks or a horizontal row of 120 125 130

blocks, with or without subtraction in the number of blocks contained in each of the rows extending at right angles to the rows whose number has been increased. This 5 modification may thus be used for impressing the form and sequence of the letters of the alphabet upon the minds of relatively young children.

It is to be noted that the blocks or pieces 10 J, L, and N of the modifications illustrated in Figures 4, 5, and 6 of the drawings are not provided with the finger holds H shown in Figures 1, 2, and 3 of the drawings, but that are provided with depressions ψ in their 15 upper surface. A stylus R is provided for use with these blocks. When the blocks are to be lifted, as in transposing or displacing the significant blocks, or removing the blank filler blocks bodily from the container; the 20 point of the stylus is inserted into the proper one of the spaces S, formed by the rounded corners of the blocks, and the blocks to be lifted is pried up out of the plane of the other blocks. In sliding the blocks to restore dis- 25 placed blocks to proper position the point of the stylus is inserted into the depressions ψ in the upper faces of the blocks.

It will be understood that the means for 30 conveniently moving the blocks are not pecu- 35 liar to the modifications with which they are shown; but that the blocks C of Figures 1 and 2 may be provided with depressions and shifted by means of a suitable stylus or the like, and that the blocks J, L, 40 and M of Figures 4, 5, and 6 of the drawings may be provided with a finger hold or button similar to that shown in Figures 1, 2, and 3.

The embodiments shown or illustrative of 45 a number of modifications and variations which may be made without departing from the central inventive idea, and the scope of the invention is therefore to be restricted only by the limitations contained in the ap- pended claims.

What we claim is:

1. A game device comprising a set of men or pieces bearing distinguishing marks for arranging the same in sequence and having 50 fixed positions within a fixed area, at least one space sufficient to accommodate one of the pieces being left blank, the object of the game being to displace at least one of the significant or sequential pieces from 55 position in sequence and to restore all the pieces to position in sequence without lifting any of the significant pieces from the surface on which they rest, and means for indicating by chance the displacement of 60 such piece or pieces.

2. A game device comprising a set of men or pieces bearing distinguishing marks for arranging the same in sequence and having 65 fixed positions within a fixed area, at least one space sufficient to accommodate one of

the pieces being left blank within such area, the object of the game being to displace at least one of the sequential or significant pieces from position in sequence and to restore all the pieces to position in sequence 70 without lifting any of the significant pieces from the surface on which they rest, and means for indicating by chance the displacement of such piece or pieces and a certain number of changes of position of the pieces 75 for restoring the significant pieces to their original sequential position.

3. In a game device a set of men or pieces bearing distinguishing marks or numbers and also bearing marks which form a complete picture or the like when the pieces are arranged in proper sequential position within a fixed area, such area having therein unoccupied space sufficient to accommodate one or more of the pieces, and means for indicating by mark or number at least one of the pieces to be displaced, the object of the game being to displace the piece or pieces indicated and to restore them and the other significant pieces to position to restore the 90 picture or the like without lifting any of the pieces from the surface on which they rest.

4. A game device comprising a container, a set of men or pieces arranged to fully occupy the space within the container, said set comprising a plurality of men or pieces bearing distinguishing marks running in sequence and at least one of the men or pieces being blank to serve as a filling piece 100 in the container, the object of the game being to displace at least one of the significant or sequential pieces upon removal of the blank piece or pieces to leave space within the container and to restore the sequential or significant pieces to proper sequential position 105 without raising any of the significant pieces from the surface within the container upon which they rest; a pointer pivotally mounted on said container, and a dial surrounding said pointer and bearing thereon the distinguishing marks of the sequential pieces, whereby the pointer may be used to indicate the piece or pieces to be displaced.

5. A game device comprising a container, a set of men or pieces completely occupying the area within said container, said set comprising a plurality of men or pieces bearing distinguishing marks running in sequence and at least one of the men or pieces being blank to serve as a filling piece in the container, the object of the game being to displace at least one of the significant or sequential pieces upon removal of the blank piece or pieces to leave space within the container and to restore the sequential or significant pieces to proper sequential position 120 without raising any of the significant pieces from the surface within the container 125

upon which they rest; a pointer pivotally mounted on said container, and a dial surrounding said pointer and bearing thereon the distinguishing marks of the sequential or significant pieces and certain arbitrary numbers to indicate a certain number of changes of position for restoring all the significant pieces to sequential position.

6. A game device comprising a container, 10 a set of men or pieces completely occupying the area within said container, said set comprising a plurality of men or pieces bearing distinguishing marks and also bearing marks which form a complete picture or 15 the like when the pieces are arranged in proper sequential position within the container and at least one blank man or piece

to serve as a filling piece in the container, the object of the game being to displace at least one of the pieces and to restore them 20 and the other pieces to position to restore the picture or the like; a pointer pivotally mounted on said container, and a dial surrounding said pointer and bearing thereon the distinguishing marks of the sequential pieces, whereby the pointer may be used to indicate the piece or pieces to be displaced. 25

In witness whereof, we hereunto set our hands.

JAMES McLENNAN.
EDWARD PEASE.
